HEATER HAVING A HELICAL FLUID CONVEYING COIL

Henry M. Paulsen, Long Beach, Calif.

Application June 2, 1945, Serial No. 597,312

3 Claims. (Cl. 122—248)

1

My present invention has to do with heaters for raising the temperature of fluids, such as petroleum oils, steam and gases, finding one of its chief uses and advantages as a heater for oils preliminary to passing them to a fractionator for separation of the components.

In general, heaters for such purposes involve tubes through which the fluids are passed, the tubes being securely mounted in a furnace structure. In conventional heater construction of this type, parallel tubes are disposed one above the other across the furnace, projecting at their ends through the furnace walls and being connected together on the outside by U-connections. In cases wherein the straight tubes are not so supported at their ends in the furnace walls, relatively expensive hangers are required. In either case provision is lacking for free movement of the tube elements due to the considerable expansion and contraction taking place in the tubes and there is no uniformity of velocity or any appreciable turbulence of the flow of the fluids while passing through the tubes. This shortcoming results in "hot spots" requiring relatively expensive or high grades of tubing and also results in deposits on the tube walls which require frequent cleaning. Also, conventional heater construction of this sort is not conducive to maximum thermal efficiency and does not permit the use of sectional furnace construction which is so desirable since the refractory lining of such furnaces must be repaired and renewed from time to time.

It is therefore among the objects of my invention to overcome those disadvantages as well as to provide additional advantages. More particularly, it is an object to provide a fluid-passing coil helically wound and disposed in a furnace in such manner that the heating flame may be projected axially through the coil in a direction counter to the flow of fluids through the coil and wherein heat reflected from the refractory walls may be utilized to the fullest advantage.

It is also an object of my present invention to provide a device of this character wherein the fluid-passing tubes are so mounted in the furnace as to provide for free expansive and contractive movement and as to require no hangers.

It is a further object of the invention to provide fluid-heating apparatus in which the fluids are passed through the tubes with uniform velocity and turbulence and in which the tubes do not require frequent cleaning. When the tubes of my invention do have to be cleaned, which is not frequently, they may be readily, economically and efficiently cleaned.

It is another object of the invention to provide fluid-heating apparatus wherein the explosion doors are disposed in an area not covered by refractory material.

2

Another object is to provide fluid-heating apparatus wherein there is minimum obstruction to the free flow of the products of combustion, thus improving the general efficiency of the device as well as enabling the use of a relatively short stack for withdrawal of the products of combustion.

Another object of the invention is the provision of fluid-heating apparatus wherein the heated fluid will leave the apparatus in most efficient condition for subsequent fractionation.

It is a further object of the invention to provide fluid-heating apparatus wherein it is possible to attain maximum tube surface with a minimum of refractory wall surface.

The particular spacing of the whorls of the tube from each other as well as from the refractory walls, which provide unexpectedly improved results, also constitutes one of the features of my invention.

While I have specifically mentioned some of its major objects and advantages, my invention contemplates additional objects and provides additional advantages, all of which will become apparent from the following detailed explanation of one of the presently preferred adaptations embraced within the broader scope of my invention as defined by the appended claims.

For purposes of the following description I shall refer to the accompanying drawings, in which:

Fig. 1 is a side elevation, some parts being shown in section;

Fig. 2 is a section on line 2—2 of Fig. 1;

Fig. 3 is a section on line 3—3 of Fig. 1;

Fig. 4 is an enlarged section on line 4—4 of Fig. 1;

Fig. 5 is a cross-sectional view showing a slightly modified structure; and

Fig. 6 is an enlarged perspective showing a fragment of the tube whorl spacer members.

Referring now to Fig. 2 of the drawings I show generally at 5 a furnace of circular cross section and comprised of two semi-circular segments or sections 5a, 5b. The lower section 5b has an arch of fire bricks 6 laid in a semi-circular metal shell 7 supported upon legs 8, spacer bricks 9 being embedded in the refractory lining and spaced apart circumferentially of the wall.

The upper section 5a consists of aligned semi-circular shell sections 17 having radial end flanges 17a secured together by bolts 17b. Secured to the side edges of the respective sections 17 are plates or flanges 18 which are bolted to parallel flange members 19 carried by the lower shell 6 by bolts 20. Fire brick lining 15 is carried by shell sections 17, the side edges of the lining being supported on the inwardly disposed portions of plates 18.

In Figures 3 and 4 is shown a discharge stack

22 for the products of combustion disposed at right angles to the longitudinal axis of the furnace, being in communication therewith through a flue 24. The stack has the usual damper element 23. The flue has openings 25 through its side walls, which openings are normally closed by explosion doors 27 hinged to the flue at 28 to swing relative thereto. The doors are yieldably held closed by some suitable means such as a spring not shown. The furnace has an end wall 30 presenting an axial opening 31 with which the flue communicates, and has an opposite end wall 33 provided with an axial opening 34 in which is disposed the fuel inlet nozzle 35.

In Figures 1 and 2 my improved fluid-passing coil, generally designated 40, is comprised of a tube helically or spirally wound into a cylindrical shape, having a tangentially disposed inlet end 42 and outlet end 44, said ends passing through openings in the side wall of the furnace.

In Figs. 1, 2, and 5 the coil 40 is supported exclusively on the spacer bricks 9, the periphery of the coil being spaced from the refractory wall preferably a distance equal to the outside diameter of the tube of which the coil is formed. The whorls of the coil are also spaced apart a like distance—that is, a distance equal to the outside diameter of the tube of which the coil is formed. For example, for a coil formed of 3½ inch outside diameter spirally wound tubing, I find a furnace whose refractory walls have an inside diameter of the order of 67 inches to be particularly suitable, the spacing of the coil from the refractory walls and the spacing of the whorls from each other being equal to the outside diameter of the tubing of which the coil is formed, or 3½ inches. To maintain this spacing of the whorls of the tube from each other and yet to allow for free relative movement resulting from expansion and contraction, I use U-shaped spacer members 50 secured, as by welding, to a metal strip 51.

In a device such as described, constituted in accordance with my invention, it will be seen that the hot products of combustion pass through the furnace in a direction counter to the flow of the fluids through the coil, so that the fluids leave the coil in the most efficient condition for subsequent fractionation. This counter flow also allows the colder fluids entering the coils to absorb heat from the colder gases of combustion, thus taking advantage of heat usually lost to atmosphere through the stack. The stack temperatures are also kept at minimum. All tube surfaces are inside the furnace and in intimate contact with the products of combustion, as well as in position to uniformly take advantage of the heat reflection from the refractory walls, thus insuring high thermal efficiency. The turbulence and even velocity of flow through the coils eliminates all possibility of local heating of the tube, or "hot spots," and reduces to a minimum deposition of residue on the tube walls. This avoidance of hot spots renders it possible to use lower grades of tubing than would otherwise be the case. The absence of bridge walls and other parts acting as baffles renders it possible to use a much shorter stack. In fact, in my device, a stack so short as not to require guy wires or equivalent support may be used. Inasmuch as the coil merely rests on the spacer bricks, all tube hangers are eliminated and absolutely free movement resulting from expansion and contraction is possible.

I claim:

1. In a fluid heater, the combination of a horizontally disposed cylindrical furnace having a refractory lining, spacer members carried by the bottom portion of the lining, said members being disposed longitudinally of the furnace and spaced apart circumferentially thereof, a cylindrical fluid-passing coil comprised of helically wound tubing, said coil being disposed axially in the furnace and having its inlet end at one end of the furnace and its discharge end at the other end of the furnace, said coil being supported by the spacer members in position coaxial with the furnace and with its periphery spaced from the lining a distance equal to the outside diameter of the tubing, combustion means disposed to project products of combustion axially of the coil in a direction counter to the direction of flow of fluid therethrough, and spacer means loosely mounted on the coil to maintain its whorls spaced apart a distance equal to the outside diameter of the tubing, said spacer means each comprising an elongated metal strip and U-shaped tube-engaging members secured to the strip at spaced points therealong.
2. In a fluid heater, the combination of a horizontally disposed cylindrical furnace having a refractory lining, spacer members carried by the bottom portion of the lining, said members being disposed longitudinally of the furnace and spaced apart circumferentially thereof, a cylindrical fluid-passing coil comprised of helically wound tubing, said coil being disposed axially in the furnace and having its inlet end at one end of the furnace and its discharge end at the other end of the furnace, said coil being supported by the spacer members in position coaxial with the furnace, combustion means disposed to project products of combustion axially of the coil, and spacer strips loosely mounted on the coil to maintain its whorls in predetermined spaced relationship to each other.
3. In a fluid heater, the combination of a horizontally disposed cylindrical furnace having a refractory lining, spacer members carried by the bottom portion of the lining, said members being disposed longitudinally of the furnace and spaced apart circumferentially thereof, a cylindrical fluid-passing coil comprised of helically wound tubing, said coil being disposed axially in the furnace and having its inlet end at one end of the furnace and its discharge end at the other end of the furnace, combustion means disposed to project products of combustion axially of the coil, and spacer means loosely mounted on the coil to maintain its whorls spaced apart a distance equal to the outside diameter of the tubing, said spacer means each comprising an elongated strip and U-shaped tube-engaging members secured to the strip at spaced points therealong.
